US0D1068255S

(12) **United States Design Patent** (10) **Patent No.:** **US D1,068,255 S**
(45) **Date of Patent:** **** Apr. 1, 2025**

(54) **COVER FOR EARPHONE CASE**

(71) Applicant: **Hamee Global Inc.**, Seoul (KR)

(72) Inventors: **Bum Joon Lee**, Seoul (KR); **Kwang Min Yuk**, Seoul (KR)

(73) Assignee: **Hamee Global Inc.**, Seoul (KR)

(**) Term: **15 Years**

(21) Appl. No.: **35/519,854**

(22) Filed: **Nov. 10, 2023**

(80) **Hague Agreement Data**

Int. Filing Date: **Nov. 10, 2023**

Int. Reg. No.: **DM/234687**

Int. Reg. Date: **Nov. 10, 2023**

Int. Reg. Pub. Date: **Feb. 2, 2024**

(30) **Foreign Application Priority Data**

Oct. 11, 2023 (KR) 30-2023-0039732

(51) **LOC (15) Cl.** **03-01**

(52) **U.S. Cl.**

USPC **D3/218**
